STEAM BOILER CONSTRUCTION

Filed Sept. 1, 1923

5 Sheets-Sheet 4

The image contains two technical line drawings of a mechanical assembly, labeled 'Figure 4.' and 'Figure 5.'.

Figure 4. This drawing shows a cross-sectional view of a complex mechanical structure. It features a central vertical shaft with a flange at the top. A large, multi-layered spiral spring assembly is wound around this shaft. The spring assembly is supported by various bearings and housing components. Numerous labels with reference numerals are present, including 102, 100, 28, 39, 32, 31, 30, 40, 68, 88, 76, 75, 28, 60, 29, 28, 30, 28, 82, 10, 82, and 28. The drawing uses cross-hatching to differentiate between different parts of the assembly.

Figure 5. This drawing is a detailed view of a specific component, likely a bearing housing. It shows a cylindrical housing with a ribbed outer surface. A large, tapered roller bearing is mounted within the housing. The bearing has a thick outer ring (100) and a thin inner ring (96). The housing features a stepped bore (98) and a shoulder (99). A label '102' points to a shoulder on the outer diameter of the bearing. The drawing uses cross-hatching to show the internal structure of the bearing and the housing.

UNITED STATES PATENT OFFICE.

JOHN G. WILL, OF CANON CITY, COLORADO.

STEAM-BOILER CONSTRUCTION.

Application filed September 1, 1923. Serial No. 660,562

This invention relates to improvements in steam boilers.

The primary object of this invention is the provision of a practical type of steam boiler 5 adaptable for use in connection with automotive vehicles.

Other objects and advantages of this invention will be apparent during the course of the following detailed description.

10 In the accompanying drawings, forming a part of this specification, and wherein similar reference characters designate corresponding parts throughout the several views:

15 Figure 1 is a side elevation of the improved boiler construction, showing the novel assemblage of parts thereof in their cooperating relation within an appropriate housing and with a novel burner mechanism.

20 Fig. 2 is a longitudinal cross sectional view taken through the improved boiler and associated construction substantially on the line 2—2 of Figure 1.

25 Fig. 3 is a cross sectional view taken substantially on the line 3—3 of Figure 1.

Fig. 4 is a transverse cross sectional view taken substantially on the line 4—4 of Figure 1.

30 Fig. 5 is a cross sectional view taken substantially on the line 5—5 of Figure 1.

Fig. 6 is a fragmentary enlarged view, in cross section, showing a novel detail of an indicator mechanism used in connection with the boiler.

35 Fig. 7 is an enlarged fragmentary view, partly in cross section, showing novel associated details of the invention, more particularly showing the burner construction.

40 Fig. 8 is a transverse cross sectional view taken substantially on the line 8—8 through the burner construction of this invention.

Fig. 9 is a cross sectional view taken through a nozzle of the oil burner construction associated with this invention.

45 In the drawings, wherein for the purpose of illustration is shown but the preferred embodiment of this invention the letter A may generally designate the entire invention which may embody a frame and hood construction B; burner construction C; novel boiler and tubing construction D; and indicator or gauge means E.

50 The frame and hood construction B will of course vary in accordance with the use for which the boiler construction D is to be put. As the boiler and tubing construction is pri-

marily designed for use in connection with the generation of steam for vehicle propulsion, the frame and hood construction B may include front and rear walls 10 and 11 respectively which may be connected in a fixed relation by bolts 12 or analogous expedients. A top wall 13 may be provided, which may include sections 14 and 15 hingedly connected, as at 16, at the center of the improved construction A; side walls 17 being hingedly connected, as at 18, to the top wall sections 14 and 15, much in the same manner as ordinary automobile hood construction. The various walls of the hood or frame construction B, because of the fact that the same provide a casing for a boiler may be of ordinary construction, or of special construction. A special construction could be that of providing each wall of a pair of spaced metal plates with asbestos or analogous insulating material therebetween. The hood construction, however, primarily provides a compartment 20 adapted to house the burner and boiler constructions C and D respectively, and insure easy access thereto by reason of the hingedly connected side and top wall sections.

Referring to the burner construction C, the same includes a substantially rectangular shaped casing or pan 25, which may be carried in any approved manner upon the support or vehicle chassis to which the hood construction B is attached. The pan 25 is, of course, mounted below the hood construction B, and provides a pocket or compartment 26 open to the compartment or chamber of the hood construction B. Hooks 28 analogous to ordinary automotive vehicle hood hooks are provided about the sides and at the front and rear of the pan 25, as a means of connecting the hood walls to the pan 25, and vice versa.

The burner construction furthermore includes a plurality of longitudinally arranged tubes 28, 29, 30, 31, 32, 33 and 34 in parallel relation within the pocket or compartment 26 of the pan 25; said tubes being arranged transversely of the hood B, or rather extending parallel with the front and rear walls of said hood construction, substantially as is illustrated in the drawings. The burner tube 34 is centrally disposed, with three of the remaining tubes on each side thereof; this tube being known as the pilot burner tube, and as will be subsequently set forth. This tube 34 has one end 35 thereof flattened,

as have also the burner tubes 30 and 33 on each side thereof. The tubes 30, 33 and 34 are all of the same lengths, and their other ends are open and provided with beveled edges 37, substantially as is illustrated in Figures 2 and 3 of the drawings and into which ends fuel is fed as will be subsequently described. The tubes 28 and 29 at the outer side of the tube 30, and the remaining two tubes 31 and 32 at the outside of the tube 33 each have both ends thereof flattened and closed. The closed ends of all of the tubes are bolted or otherwise secured to brackets 39 provided in the burner box or pan 25, substantially as is illustrated in the drawings. The intermediate tubes 33 and 34 are longer than the remaining tubes, and at their open ends extend through a wall 39^a of the burner box 25. Each of the tubes 29 to 34 inclusive are transversely slotted with a series of slots in the top thereof, throughout their length within the burner box 25, and through which fuel emits to permit the proper ignition thereof.

Fuel supply means 40 is provided in connection with the burner construction C, which includes a pilot fuel tube 41 disposed directly over the pilot burner tube 34 and leading through the walls 38 and 39^a of the burner pan 25, having a nozzle 43 downturned into the open end of the pilot burner tube 34, and the construction of which nozzle will be subsequently described. That portion of the fuel feed means used to supply fuel to the open end of the tube 33 includes a length of tubing 44 which extends over the burner tube 32 for the length thereof, and adjacent the side wall 39^a of the burner pan 25 is bent and returned in a length 45 directly over the burner tube 33. Adjacent the opposite side wall 38 of the burner pan 25 the tubing is bent and extends for a length 46 over the central tube 34, substantially as is illustrated in Figure 5, and extends through the wall 39^a of the burner box or pan 25, having a nozzle 47 thereon which supplies fuel to the open end of the burner tube 33. The tube length 44 has an exit through the side wall 38 of the burner box 25, and is connected to a transverse length of piping 48 which has communication therewith and which leads into the burner box 25, having a length 49 thereof which extends longitudinally over the burner tube 29, and adjacent the wall 39^a is bent in a return length 50 over the burner tube 30. The length 50 adjacent the wall 38 of the burner box 25 and while still within the compartment of said burner box is bent to extend for a length 51 over the burner tube 34, substantially as is illustrated in Figure 5 of the drawings, at its free end extending through the burner box wall 39^a and having a nozzle construction 52 thereon to supply fuel to the open end of the burner tube 30.

The fuel to be used is oil, which enters at 55 into the lengths of tubing having the nozzles 47 and 52 thereon. This oil is conveyed backward and forward longitudinally above the burner tubes so that the oil will be preheated to a vaporized condition prior to its spray into the open ends of the burner tubes 30 and 33. The burner tube 34 and its individual fuel supply tube 41 are provided as a means of providing a pilot flame for the burner construction C. The tubes 28, 29, 30, 31, 32 and 33 are in intercommunicating relation by means of transverse tubular connections 56, substantially as is illustrated in Figure 5 and the cross sectional view of Figure 8. The tubular connections 56 which extend to communicate the burner tubes 30 and 33 extend transversely through the central or pilot burner tube 34 in noncommunicating relation therewith. It can thus be seen that the vapor fuel will be fed in equal pressure within all of the burner tubes except the central pilot burner tube 34, which receives an independent supply of vapor fuel from the tube or conduit 41 and its nozzle 43.

The construction of the nozzles 43, 47 and 52 are identical. Each of the same includes a right angled connection 57 fitted at the end of the burner tube, providing a depending screw threaded tubular stem 58 having a clamping nut 59 adjustable thereon. A piece of copper or analogous pliable tubing 60^a is provided as the nozzle portion of each of the nozzle constructions, which is secured by means of the clamping nut 59 to the connection 57. The lower end 61^a of the tubing 60^a is crimped, flat, or rolled to a closed end, and in the side of the nozzle tubing 50 which faces the chamber of the burner tube a duct 62^a is provided, through which the fuel spray is forced into the interior of the burner tube.

The boiler and tubing construction D is of course located within the hood compartment 20 and immediately over the burner tubes above described. The arrangement D, in the main, includes a plurality of tubular headers 60, 61, 62, and 63 arranged in a vertical plane, one over the other, the header 60 being the lowermost and longest, while the header 63 is uppermost and of the same length as the intermediate headers 61 and 62. All of the headers are arranged on horizontal axes. The lowermost header 60 extends transversely through the side walls 17 of the hood construction B, and at its ends rests upon suitable brackets 65 which may be appropriately welded to the burner pan construction 25 or to other frame construction, to support the lower header 60 in a secure relation. The headers 60, 61, 62 and 63 are in intercommunicating relation at each end thereof, as by means of detachable couplings or union connections 66, 130

which are of a strong and durable anti-leak type. The ends 67 of each of the headers are detachable, being connected in anti-leak connection at the ends of each of said headers by means of stay rods 68 which extend longitudinally and axially through said headers in the well known manner, as illustrated in Figure 2 of the drawings. A blow off valve 70 may be provided exteriorly of the housing construction for the boiler arrangement at one end of the lower header 60 which extends outwardly of the hood construction B, substantially as is illustrated in Figure 2 of the drawings. Each end wall 15 of each of the headers is preferably provided with a detachable plug 72 therein whereby access may be had to the interior of the headers for cleaning purposes. The headers are arranged in parallel relation 20 with the burner tubes, in a plane centrally arranged over the pilot burner tube 34; the headers being of considerable capacity, and extending to the extreme top of the compartment 20 defined by the hood construction. 25

A pre-heating arrangement is provided in connection with the boiler construction which includes a pair of spirally wound coils 75 and 76, each wound in a plane and disposed at opposite sides of the headers in close proximity thereto. The tube 75 provides an inlet 77 through which water is fed and which flows spirally about the convolutions of the coil 75 toward the center 35 thereof, becoming preheated. At its center the coil 75 is outturned, as at 78, at right angles to the plane of the coil 75, and is connected by a detachable union coupling 79 to the centrally offset end 80 of the other coil 76. The water flows across this connection into the coil 76 and from the center thereof about its convolutions to the outer convolution thereof; the outer convolution thereof being connected by a detachable coupling 81 to the side of the lowermost boiler header 60; the preheated water thus entering the compartment of the lower header 60 first and being subjected to heating therein. The level of the water is, of course, 40 such as to fill the intermediate headers 61 and 62; the upper header 63 being utilized as a steam dome.

A series of spiral coils 82 are provided at the outer side of each of the preheating coils 75, and 76, in intermeshing relation, at their upper ends each having a connection, as by detachable union joints 83, with the header 63. At their lower ends each of the coils 82 has a detachable connection, as by a union joint 84, with the lowermost header 60. These coils 82 may be of any approved number of convolutions, and extend in intermeshing relation at each side of the boiler arrangement to connect the uppermost header 63 with the lowermost header 60.

These coils are mainly steam generating coils in that the flames of the burner play thereabout. It can thus be seen that all steam from the headers and from the coils heretofore described passes into the uppermost header 63. 70

Above the header 63, and in a horizontal plane, a spirally wound coil 88 is positioned, which at its center has a laterally extending offset for detachable connection, as by a union 89, to the top wall of the upper most header 63, and adapted to receive steam from the uppermost header 63 to be superheated as it passes around the various convolutions of the coil 88. The super-heated steam passes off through an outlet tubing 90 to a desired location where it may aid in the propulsion of the machinery desired. 75

Referring to the indicating means E, a vertically disposed length of pipe or tubing 92 is placed exteriorly of the hood or casing construction for the boiler arrangement, at its upper end having communication with the super-heated steam outlet 90, and at its lower end having connection with the water compartment of the lowermost header 60. The water in the various headers of the boiler arrangement of course should rise to a level below which the same should not fall. This same level of water will, of course, occur in the vertical pipe 92. Upper and lower couplings 94 and 95 respectively are secured to the vertical pipe length 92, at predetermined elevations thereon; said couplings 94 and 95 being so connected on the pipe length 92 as not to have communication with the passageway 96 extending through the piping 92, but being soldered or otherwise connected by end plates 98 to the tubing 92 as to provide an enclosed compartment 99 circumferentially about the pipe 92. Gauge tubes 100 and 101 are respectively connected to the couplings 94 and 95, by approved means 102, as to have communication with the enclosed compartments 99 of said couplings. Appropriate pressure gauges 104 and 105 may be placed upon the ends of the tubes 100 and 101 respectively. These tubes, as well as the enclosed compartments with which they communicate may receive an expandible liquid, such as cylinder oil, mercury, alcohol, or the like. Normally the height of water should be above the uppermost coupling 94. Incident to exhaustion by passing off of steam the water level may flow to an undesired level, below the points on the pipe 92 on which the coupling 94 is placed. This lowering of the level of water will permit the super-heated steam to pass into that portion of the pipe 92 about which the coupling 94 is placed, which considerably raises the temperature of the oil or other expandible liquid within the compartment 99, tending to expand the same and to indicate upon the gauge 104 that the water level has fallen. 110

115

120

125

130

below the coupling 94, and that the boiler requires replenishing. Should the water level fall below the coupling 95 it will warn the operator that the boiler is in extreme need of water; the gauge 105 operating on the same principle as the gauge 104. The couplings 94 and 95 may be exteriorly covered with wire mesh in close fitting relation thereon as a means for quick air cooling of the same. A conduit 107 may be connected in the vertical pipe 92 between the couplings 94 and 95, which may have an ordinary automatically operated expansion water feed regulator thereon to maintain the water in the boiler at a desired level.

At the front of the hood construction B an exhaust manifold or outlet 110 may be positioned, which may be of flaring formation, having a connection with the compartment 20 of the hood construction at the top thereof, to permit the waste products of combustion to pass therethrough. The flame of the burner arrangement, as to intensity, may be regulated by any of the automatic regulators now found on the market.

From the foregoing description of this invention it is apparent that a boiler has been provided, the parts of which are cooperatively and compactly arranged as to permit the effective generation of super-heated steam. The coils and headers are so arranged that the steam generation may take place in as small a place as possible; the water to be turned into steam being exposed over a relatively great surface area incident to the novel arrangement of coils and headers above the burner arrangement. An important feature of the improved boiler construction is that the individual units thereof are relatively detachable and accessible. The gauges 104 and 105, in the instance where the boiler is used for automotive vehicle propulsion may be placed upon a dash or other suitable location.

Various changes in the shape, size, and arrangement of parts may be made to the form of invention herein shown and described, without departing from the spirit of the invention or scope of the claims.

I claim:

1. A boiler construction comprising a series of headers arranged one over the other in a vertical plane, a pair of preheating coils disposed one at each side of the headers, each of said coils being wound with the convolutions all in a plane and parallel with the plane of the headers, communicating means extending centrally between said coils, water inlet means for one of said coils, and means communicating the other of said coils with the lowermost header of said boiler arrangement.

2. A boiler arrangement comprising a main boiler defining a plurality of superposed intercommunicating headers in the

same vertical plane, a preheating construction embodying coils disposed at each side of the headers, each of said coils embodying a plurality of convolutions disposed in the same vertical plane, means communicating said coils with the lowermost header, and a super-heater coil mounted above and in communicating relation with the uppermost header. 70

3. A boiler construction comprising a series of parallel superposed headers in a vertical plane, means detachably connecting said headers in communicating relation, the uppermost of said headers providing a steam dome, a pre-heater arrangement providing a pair of coils one at each side of the plane of the superposed headers and each providing a series of convolutions in the same vertical plane, one of said coils providing a water inlet and the other of said coils having communication with the lowermost header to supply water thereto, a series of coils disposed at each side of the plane of said headers connecting the uppermost header or steam dome directly with the lowermost header, and a superheater coil disposed over the uppermost header providing a plurality of convolutions disposed in the same horizontal plane. 85 90

4. In a boiler construction the combination of a plurality of horizontally disposed headers having means intercommunicating the same intermediate their ends, said headers being arranged in a vertical plane, pre-heating coils arranged at each side of the plane of the headers each having the convolutions thereof disposed in a vertical plane parallel with the plane of the headers and closely placed adjacent the sides of said headers, said coils being communicated centrally thereof, and one of said coils at the outer end thereof being connected with the lowermost header, spiral coils connected at their lower ends with the lowermost header and extending upwardly at each side of the plane of the headers outwardly of the planes of the preheating coils, a plurality of the coils last mentioned being provided at each side of the plane of the headers and extending in an intermeshing relation upwardly 110 for connection at their upper ends in the uppermost header, and a superheater coil comprising a plurality of convolutions all disposed in the same horizontal plane, the said superheater coil at the center thereof 115 being communicated with the uppermost header intermediate the ends of the header. 120

5. In a boiler construction a plurality of horizontally disposed superposed headers in a vertical plane having communicating coupling connections therebetween, more than two of said headers being provided, a spiral preheating coil having the convolutions thereof disposed in a vertical plane closely spaced at a side of the plane of said headers 125 130

having an end communicating into the lowermost header for feeding preheated water into said lowermost header, a vertical spiral coil closely spaced adjacent the first mentioned coil at the opposite side of the same from said headers, said second mentioned coil having the lower end thereof communicating into the lowermost header and the upper end thereof communicating into the uppermost header, and a horizontal superheating coil of spiral formation having the convolutions thereof all disposed in the same horizontal plane immediately closely above the upper header and communicating with said upper header. ¹⁰

JOHN G. WILL.
